FIG. 1 is a front perspective view of a first embodiment of
the golf bag sign as claimed herein;

FIG. 2 is a front plan view thereof;

FIG. 3 is a rear plan view thereof;

FIG. 4 is a right side plan view thereof;

FIG. 5 is a left side plan view thereof;

FIG. 6 is a top plan view thereof;

FIG. 7 is a bottom plan view thereof;

FIG. 8 is a front perspective view of a second embodiment of the golf bag sign as claimed herein;

FIG. 9 is a front plan view thereof;

FIG. 10 is a rear plan view thereof;

FIG. 11 is a right side plan view thereof;

FIG. 12 is a left side plan view thereof;

FIG. 13 is a top plan view thereof;

FIG. 14 is a bottom plan view thereof;

FIG. 15 is a front perspective view of a third embodiment of
the golf bag sign as claimed herein;

FIG. 16 is a front plan view thereof;

FIG. 17 is a rear plan view thereof;

FIG. 18 is a right side plan view thereof;

FIG. 19 is a left side plan view thereof;

FIG. 20 is a top plan view thereof; and,

FIG. 21 is a bottom plan view thereof.

The broken lines are included for the purpose of illustration only and form no part of the claimed design.
